TRAVELING STEP LADDER

Florentin J. B. Antonietti, Herzogenaurach, Germany

Application March 11, 1955, Serial No. 493,600

Claims priority, application France March 18, 1954

2 Claims. (Cl. 228—15)

The present invention relates to a device permitting the movement of ladders without it being necessary to climb down therefrom, in particular double-ladders or folding ladders, the ones used for example by painters, plasterers, decorators, glaziers, etc.

Its purpose is to avoid stepping down, moving and stepping up the ladder, so much tiring operations and losses of time for the user of the ladder who whishes to move from one part of his work to another.

The device according to the invention is essentially comprised of two propelling shafts, two adherent shoes at the lower ends thereof, pivoting means provided on said ladder for receiving said shafts with a free lengthwise movement thereof, and locking means for engagement of said shafts.

In a preferred embodiment, the device according to the invention also comprises resilient means, and abutments on said shafts, said resilient means being placed between said abutments and said locking means, so as to engage said latter means in locking position for pushing said shafts downwards.

Other characteristics and advantages of the present invention will appear from the following description, with reference to the accompanying drawings, given only as illustration and showing one embodiment of the invention.

Figure 1 is a perspective view of the ladder according to the invention.

Figures 2 and 3 are detailed views of the device enabling the movement of the ladder.

Figures 4 and 5 are also detailed views, showing the stopping devices and the safety locks completing this stopping.

In the embodiment shown, the device enabling the moving of the ladder 1 is essentially made up of two propelling shafts or tubes 2 and 2a, attached to each side of the ladder and slideable in plates 3 and 3a. These plates swivel on axles 4, attached to the cross-pieces 5 holding the double-ladder. The tubes 2 and 2a slide freely in the rings 6 fixed to the plates 3 and 3a (Figs. 1, 2 and 3).

The propelling shafts or tubes 2 and 2a end at the bottom in an adherent shoe 7 and 7a.

One easily understands that by means of these components the user may move his ladder without stepping down therefrom. Indeed, in operating the tubes 2 and 2a somewhat in the manner of ski-sticks he is able, by exerting pressure on the ground, through the adherent shoes 7 and 7a, to advance, reverse or even turn the ladder he is standing on.

2

By lowering and properly sliding tubes 2 and 2a to find a point of support in front or in back, the user is able to advance or reverse his ladder. To turn it suffices to operate one of the propelling shafts in a direction opposite the other, depending upon whether he wishes to turn left or right.

At rest the propelling shafts or tubes 2 and 2a are brought at right angle to the ground and can be held in this position by the side parts forming stops 8 and 8a. 10 These parts are attached in such a manner as not to disturb the movement of the shafts 2 and 2a when they are freed therefrom (Figs. 4 and 5).

To secure the ladder against motion, a safety device made of a coil spring 9, may be slipped on the tubes 15 2 and 2a, below their handles 10 (Fig. 5).

The spring 9 is attached at one end 11 thereof to its supporting tube; its other end receives a washer 12 arranged to engage the lower edge of the stop part 8 which is shaped accordingly in 13.

20 When the propelling tubes 2 and 2a are brought to a position at right angle to the ground, the washers 12 of their safety locks follow the curved edges 13, simultaneously compressing the spring 9 which locks the tubes against motion. The user must only pull lightly 25 on the handles 10 to unlock the tubes by releasing the springs 9.

The ladder is of course mounted on pivotable casters 14 to enable easy operating and moving.

30 The above embodiments have only been given by way of example and many changes may be brought therein without departing from the scope of this invention.

I claim:

1. In a ladder having a device enabling its moving without descending therefrom, two propelling shafts, two 35 adherent shoes at the lower ends thereof, two cross-pieces holding the ladder in spread position, pivoting means provided on said cross-pieces for receiving said shafts with a free lengthwise movement thereof in a vertical plane, and locking means for locking said shafts 40 in a vertical position, said shafts being pushed downwards with a resilient force in said locking position.

2. In the ladder of claim 1, spring means provided on 45 said shafts, and abutments provided on said shafts below said locking means in spaced relationship therewith, said spring means being placed on said shafts above said abutments, said spring means being engaged and compressed between said abutments and said locking means in locking position, said locking means being provided 50 at the upper ends of the ladder, somewhat below the upper ends of said shafts.
